ATTORNEY.

UNITED STATES PATENT OFFICE.

GEORGE W. BOTHAM, OF MADISON, WISCONSIN.

STOCK-TANK HEATER.

1,234,695.

Specification of Letters Patent. Patented July 24, 1917.

Application filed October 2, 1916. Serial No. 123,444.

To all whom it may concern:

Be it known that I, GEORGE W. BOTHAM, citizen of the United States, residing at Madison, in the county of Dane and State of Wisconsin, have invented certain new and useful Improvements in Stock-Tank Heaters, of which the following is a specification.

My invention relates to stock tank heaters; and the objects of my invention are—

First,—to provide a casing that will expose the greatest proportion of heating surface to the water in the tank;

Second—to afford convenient means for removing the grate and ash pan;

Third—to cause all air entering the heater to pass through the fuel, and

Fourth—to eliminate pipe dampers by means of a telescoping smoke stack.

I attain these objects by the mechanism shown in the accompanying drawings in which—

Figure 1 is a plan with top removed.

Fig. 2 is a vertical cross-section on line A—B, Fig. 1.

Fig. 3 is a side elevation partly in section.

Fig. 4 is a plan of a portion of the top plate.

Similar numerals refer to similar parts throughout the several views.

The casing, 1, is a metallic water tight box open on top, a distance from the front end. On the inside a partition, 2, is pro-

vided, secured to the two sides of the cas-

ing and extending downward approximately two-thirds the distance to the bottom, thence turning inward, forming a ledge, 3. Upon

said ledge, 3, is disposed the front end of a

grate, 4; cotter pins, 5, securing the grate to the ledge. The grate, 4, comprises a

series of parallel bars and apertures con-

nected at the front end by the band, 6, and

at the rear end by the margin, 7, the fire

45 wall, 8, and ash pit wall, 9. The elements, 4, 5, 6, 7, 8, and 9, being an integral cast-

ing, constitute an important part of my in-

vention, and provide a very convenient

means for cleaning the fire, in view of the

50 fact that by inserting a hook between the

grate bars and under the margin, 7, the

grate can be raised and dropped, completely

removing all ashes from the fuel and de-

positing same in the ash pan, 10. The said

55 pan can be taken out of the casing by rais-

ing the grate and section, 11, of the top

plate. The top plate complete, comprises sections 11, 12, and damper door, 13, the sections 11 and 12 positioned on top of the casing by depending flanges 23 or equivalent convenient means; and the damper door resting upon the top of the case. The said damper, between the hinge member on one side and the adjacent lug on the plate, 11, is provided with a spring, 14, surrounding the pivot bolt, 15, causing sufficient friction between the hinge members to hold the damper in the most minute adjustment. Equidistant from the back edge and the sides of the top plate member, 12, is located a pipe flange, 16, and a smoke stack, 17 extends upward from the outside thereof; and inside of said pipe flange is disposed, in sliding relation, a draft controlling pipe, 18, with a flange 23 projecting outward around the top thereof, loosely fitting the inside of the stack. The pipe, 18, is provided with the rod, 19, secured thereto near the bottom and passing upward through the top plate with a chain 25 attached for holding in the desired position by connecting one of the links of the chain to a hook 24 on the side of the smoke stack.

To start the fire, place desired fuel on grate, 4, slightly raise damper, 13, and raise draft pipe, 18 to highest position, giving a draft as indicated by arrows, 20, 21, Fig. 3; and when the fire is sufficiently under way lower draft pipe, 18 to desired point producing currents, 20, 22, Fig. 3. Another advantage attained in stock tank heater efficiency is the fact that pipe, 18, has a dead air space between it and the outer pipe, 17. The gases from the fire more readily heat the inner pipe in cold weather and thereby facilitate the starting of the fire, and furthermore, the pipe being surrounded by hot gases, a much better draft can be maintained.

I claim—

1. In a device of the kind described in combination with a water tight casing; a partition plate adjacent one end; a ledge at the lower end of the plate adapted to support a grate; a grate comprising bars; fire and ash pit walls; a plurality of cotter pins hingedly securing said grate to said ledge allowing the grate to be raised and dropped for cleaning the fire; a top plate covering the casing; a smoke stack extending upward from the cover; a slidable draft pipe disposed inside the smoke stack and

depending therefrom; means for holding the draft pipe in the desired position.

2. In a device of the kind described in combination with a water tight casing, a
5 partition wall; a grate resting on the partition wall; a top plate or cover comprising three sections of unequal lengths; a
10 damper door being the smaller of the sections hingedly secured to the contiguous section; a spring disposed between the hinge

members causing a friction sufficient to counterbalance the door and allow of its being minutely adjusted.

In testimony whereof I affix my signature in the presence of two subscribing 15 witnesses:

GEO. W. BOTHAM.

Witnesses:

A. J. BUENZLI,
THEO. A. WALLER.
